UNITED STATES PATENT OFFICE.

FRANK H. MILLS, OF RENOVO, PENNSYLVANIA.

ENGINE-STARTER.

1,096,314.

Specification of Letters Patent. Patented May 12, 1914.

Application filed February 20, 1913. Serial No. 749,751.

To all whom it may concern:

Be it known that I, FRANK H. MILLS, a citizen of the United States, residing at Renovo, in the county of Clinton and State of Pennsylvania, have invented certain new and useful Improvements in Engine-Starters, of which the following is a specification.

This invention has reference to improvements in engine starters, and is designed more particularly for use in connection with the power engines of automobiles.

The object of the present invention is to provide a starter which may be employed with multi-cylinder engines, and will act selectively to charge that cylinder having the piston positioned for the power stroke, so that upon the production of a spark in the then charged cylinder an explosion will occur and a suitable impulse be given to the engine to cause the establishment of the proper cycle of operations, the starter of the present invention being capable of supplying the cylinders in succession with charges until the regular action of the engine has been brought about.

The invention comprises a valve structure connected to the different cylinders of the multi-cylinder engine, and the construction is such that an explosive mixture under suitable compression may be supplied to the valve structure and by the latter automatically distributed or directed to such cylinders as shall have their pistons in the proper position for starting in the proper direction when supplied with a compressed explosive charge and such charge is ignited.

The present invention is adapted to multi-cylinder engines of the four or six cylinder four cycle type, these being the types most in use, and while not confined in its adaptation to the two particular types of multi-cylinder engines, will be described in connection with the two forms of engines mentioned, since the principles of the invention are amply illustrated thereby.

The invention will be best understood from a consideration of the following detailed description, taken in connection with the accompanying drawings, forming part of this specification, with the further understanding that while the drawings show a

practical form of the invention, the latter is not confined to any strict conformity with the showing of the drawings, but may be changed and modified so long as such changes and modifications mark no material departure from the salient features of the invention.

In the drawings: Figure 1 is a plan view of the valve structure of the present invention adapted for use in connection with a four cylinder explosion engine. Fig. 2 is a section on the line 2—2 of Fig. 1 with certain other parts added and shown partly in section and partly in dotted lines. Fig. 3 is a section on the line 3—3 of Fig. 2. Fig. 4 is a plan view similar to Fig. 1 but showing an arrangement adapted to a six cylinder engine. Fig. 5 is a section on the line 5—5 of Fig. 4.

Referring to the drawings, there is shown a valve body 1 in the form of a block of substantially rectangular outline, and of somewhat less thickness than width and length, but the particular shape of the valve casing is of no material moment. This valve casing 1 is provided with a cover 2 and incloses a series of chambers 3 disposed about a common center, these chambers being in communication with a common sub-chamber 4 through respective ports 5 formed on the end corresponding to the chambers 3 with valve seats 6. Leading from each chamber 3 is a pipe 7 including a check valve 8 closing toward the respective chamber, and each pipe 7 is carried to the intake of a respective engine cylinder 9, but one cylinder 9 being shown in the drawings, and that showing being in connection with Fig. 1, but the indicated cylinder 9 may be considered as indicative of an explosion engine of suitable type having a number of cylinders corresponding to the number of chambers in the valve casing.

Extending axially through each chamber 3 is a valve stem 10 having a continuation 11 entering a guiding pocket 12 in line with the longitudinal axis of the respective chamber 3 but located in that wall of the chamber 4 remote from the chambers 3. That end of each valve stem 10 remote from the continuation 11 is carried through a suitable passage 13 in the cover 2. Within the chamber

3 each valve stem 10 has a valve 14 and a disk or piston 15. Each port 5 is materially smaller in diameter than the diameter of the respective chamber 3 and the valve 14 is of a 5 diameter to be adapted to the respective seat 6, while the disk 15 is of materially greater diameter than the valve 14 and is fitted to the respective chamber 3 to move therein in practically gas-tight connection therewith 10 under the pressures employed.

Secured to the valve casing in a position corresponding to the common center of the valve chambers 3 is a post 16 which may be in the form of a rod threaded at one end to 15 seat in a correspondingly threaded socket 17 formed in the valve casing and at the other end threaded to receive a nut 18.

At an intermediate point the rod 16 is squared, as shown at 19, or otherwise suitably formed. Mounted on the squared portion 20 of the rod 16 is a spider composed of arms 20 which in the structure shown in Fig. 1 radiate from a central point in ninety degree relation, and each arm at the outer end 25 is enlarged, as shown at 21, to engage the exposed end of a respective valve stem 10 where such stem projects through the valve casing cover 2. The rod 16 is provided with a flange or collar 22 which may be rounded 30 on the face presented toward the spider, and the latter is formed immediately about the rod 16 with a groove or seat 23 adapted to the flange 22, so that the spider may be rocked with the flange 22 serving as a pivot 35 support. Between the nut 18 and the spider there is confined a spring 24 in surrounding relation to the rod and engaging at one end against the spider and at the other end against a washer 25 held to the rod 16 by 40 the nut 18.

The constant action of the spring is to press the spider toward the cover 2 and the ends of the spider arms engaging the valve stems 10 force the valves 14 into engagement 45 with the seats 6, so that under the conditions assumed the chamber 4 is closed against communication with the chambers 3 and the valves 5 are at some little distance from the cover 2, while the pipes 7 communicate with 50 the chambers 3 in the space between the two valves.

Connecting with the chamber 4 is a pipe 26 extending to a pump 27 shown in dotted lines in Fig. 2, but which may be taken as 55 indicative of any device wherein there is or may be contained a supply of an explosive mixture which under appropriate pressure will be directed to the chamber 4 by the pipe 26. Assuming that the pump 27 is employed, 60 then the pipe 26 includes a check valve structure 28 connected by a pipe 29 to any suitable source of fuel, say to the carburetor of an automobile. Where the pump 27 and check valve 28 are not employed a tank of

compressed fuel may be provided, it being 65 possible with the starter of the present invention to employ the tank of compressed gas employed for lighting purposes for supplying the compressed gas for starting purposes. Assuming that the explosion engine 70 is standing still, then a certain one of the pistons in a four cylinder engine will be in a position in the cylinder permitting an explosion within such cylinder to start the engine forwardly, and, moreover, the explosion chamber of the particular cylinder under consideration will be of minimum size due to the close approach of the piston to the corresponding head of the cylinder. Assuming that the starting device is provided with 80 a pump 27, then the operator manipulates the pump in a manner to cause a suction which will draw gas through the pipe 29 into the pipe 26, and from thence into the cylinder of the pump 27, the valves 14 remaining closed. In the reverse movement of the pump the check valve 28 closes and the charge is forced through the pipe 26 into the chamber 4 forcing its way through the ports 5, the valves 14 opening, but that chamber 3 connected with the engine cylinder having the smallest effective explosion chamber becomes equally filled with compressed gas at a higher pressure than in the other cylinders where the gas readily flows into 90 the respective engine cylinders. A superior pressure within the particular chamber 3 under consideration acts upon the disk 15 and since the other disks 15 are not subjected to like pressure, the valve stem 10 of the first-named disk 15 rises, causing the spider 95 20 to rock thus moving the opposite valve stem 10 in a direction to close the valve 14, after which the difference in areas between the closed disk 14 and the opposite disk 15 105 maintains the valve 14 in the closed position so long as the superior pressure is maintained in the engine cylinder connected to the chamber having the open valve 14. If it be assumed that the chamber 3 under consideration as having its valve 14 open be that chamber to the right of Fig. 1, then the chamber 3 at the left will be the one having the valve 14 closed. If it be assumed that the engine cylinders are so related that 110 the rotation of the engine is such as to cause the cylinders to act progressively in a substantially clockwise direction as viewed in Fig. 1, then the lower chamber as viewed in Fig. 1 will have a higher pressure initially 115 produced in it than in the succeeding chambers in order, so that the spider will be rocked on an axis perpendicular to a radial line intermediate of the right hand chamber 3 and the lower chamber 3 while the other 120 two chambers will have their valves 14 closed, the valves 14 of the first two chambers being open. Suppose, now, that a spark 125

be produced in the cylinder connected to the right hand chamber 3 of Fig. 1. An explosion will occur and the engine crank shaft will be given a forward impulse, since the charge 5 already within the cylinder under consideration is a compressed charge, and, therefore, inflamed by the passage of the spark. The first impulse given to the engine results in the compression of the already introduced 10 charge in cylinder No. 2 in the order of action of the engine, and as the piston of this cylinder is then moving toward the closed end of the cylinder the charge is compressed and by the time the explosion in the first 15 engine cylinder has expended its force the spark passes to the second cylinder in order and the introduced charge becomes inflamed and the explosion takes place. Back firing through the pipes 7 cannot occur because of 20 the check valves 8.

In the case of a six cylinder engine, six 25 chambers 3 are provided, as indicated in Fig. 4, and the valve casing indicated at 1^a is correspondingly enlarged. A post 16^a is provided and may in all essential respects 30 be similar to the post 16 of Fig. 4. The structures differ, however, in that there are two spiders 30, 31 in superposed relation on the post 16^a and the spider 31 is formed 35 with a central boss 32 seating in a corresponding concavity 33 on the spider 30, and each spider may be more or less rounded out where traversed by the post 16^a, so as to permit the rocking of the spiders. Instead 40 of the spiders being four-armed, as in Fig. 1, they are each triangular in shape and are so arranged as to bear on alternate valve stems. If a valve stem be raised in the structure shown in Fig. 1, then the spider 45 will rock and cause the depression of the other two valve stems controlled by the same spider. In this manner the one of the disks 15 in the chamber connected to the cylinder having the smallest effective explosion 50 chamber at the time is raised and the valves 14 in the corresponding chambers controlled by the same spider are closed. The next chamber 3 in order is controlled by the other spider, but, like the structure shown 55 in Fig. 1, the said next chamber in order has its disk 15 actuated to move the valve 14 away from its seat, thus rocking the spider and seating the valves 14 of the other chambers. It will be seen, therefore, that 60 the action of the structure of Fig. 4 is practically the same as that of the structure of Fig. 1, although the structure of Fig. 1 is designed for a four cylinder engine and that of Fig. 5 for a six cylinder engine. The 65 mounting of one spider on the other and the tapering passages through the spiders where surrounding the post 16^a provide for the rocking movements without turning movements of the spiders.

As soon as the engine is started the starting apparatus of the present invention becomes inactive, the spring 24 forcing the valves 14 to their seats in the absence of superior pressure in the chamber 4, and any tendency for the production of sub-atmospheric pressure or suction within the chambers 3 only serves to hold the valves 14 more firmly to their seats, since atmospheric pressure upon the valves 15 is superior and acts in opposition to atmospheric pressure upon the valves 14 in a direction tending to open these valves. The pressure within the cylinders due to the explosions therein cannot be transmitted to the chambers 3 because of the check valves 8, and the effect of the production of sub-atmospheric pressure within the cylinders on the suction strokes is ineffective to the valves within the chambers 3 for the reasons stated.

What is claimed is:—

1. A starter for multi-cylinder engines comprising a valve structure having as many valves as there are cylinders to the engine and each valve controlling the admission of fluid under pressure to the respective engine cylinders, and connections between the valves for causing a movement of one valve to move other valves in the reverse direction, and means for directing fluid under pressure to all the valves, said valves being differential valves and responsive to effectively different fluid pressures.

2. In a starter for multi-cylinder engines, a valve structure provided with as many chambers as there are cylinders to the engine and with a chamber common to all the first-named chambers and communicating with each first-named chamber through a port of less area than the cross-sectional area of the respective first-named chamber, a valve member within each first named chamber having a valve and a disk thereon of different areas and each first named chamber being connected to a respective cylinder, connecting means between the valve members for causing the active movement of one valve member to maintain the valves of the other valve members in the closed position with respect to the port between the second-named chamber and the respective ones of the first-named chambers, and means for supplying fluid under pressure to the second-named chamber.

3. In a starter for multicylinder explosion engines, a valve structure having a plurality of separate chambers equal in number to the cylinders of the engine and each connected to a respective cylinder, a chamber common to all the first-named chambers and communicating therewith through ports individual to the chambers and each of less area than the cross-sectional area of the respective chamber, a valve member in each

chamber having a valve adapted to the port in said chamber and a disk or piston of larger area corresponding to the cross sectional area of the chamber, a spider engaging the valve stems and movable in response to the active movement of any valve to hold their valves in the closed position, and means for supplying fluid under pressure to the second-named chamber.

10. 4. A starter for multi-cylinder explosion engines provided with as many valve chambers as there are cylinders to the engine with each chamber connected to a respective cylinder and said connection provided with means for preventing return flow of fluid from the cylinder to the valve chamber, a differential valve in each chamber, means for causing the active movement of one valve to control the active movements of the other valves, and means for directing fluid under pressure to the respective valves.

5. A starter for multi-cylinder explosion engines comprising a valve structure having as many valve chambers as there are engine cylinders and each valve chamber having communicating connections with a respective engine cylinder, a differential valve in each chamber, a rockable spider engaging the several valves and having a normal tendency to maintain the valves in the closed position, and means for directing fluid under pressure to the valves to act selectively thereon in opposition to the normal 35 tendency of the common valve engaging means.

6. A starter for multi-cylinder explosion engines including as many differential valves as there are engine cylinders, a means common to all the valves for directing fluid under pressure thereto, each valve controlling the passage of fluid from the common means to the respective cylinders, and interconnected means for the valves constructed 45 to cause the active movement of the valve to opposed active movements of other valves.

7. In a starter for multi-cylinder explosion engines, a valve casing having a series of 50 valve chambers therein, and another chamber common to all the valve chambers and communicating therewith through ports individual to the valve chambers, and each of less area than the cross-sectional area of 55 the respective valve chamber, a valve stem in each valve chamber and provided with a valve adapted to the port between the valve chamber and the common chamber and with a disk or piston fitting the valve chamber 60 and movable therewith, the disk or piston being of larger area than the valve, a connection between each valve chamber and the respective cylinder, said connection including a check valve closing toward the

valve chamber, a stem or post in the valve structure intermediate of the chambers, a rockable device carried by the post and engaging the valve stems, a spring acting on the rockable device and tending to maintain the valves in closing relation to the ports between the valve chambers and the common chamber, and means for supplying fluid under pressure to the common chamber.

8. A starter for a four cylinder explosion engine comprising a valve structure having as many differential valves as there are cylinders and a distributing chamber communicating with all the valves, each valve controlling the passage of fluid from the distributing chamber to the respective cylinders, means for supplying fluid under pressure to the distributing chamber, and a rockable spider carried by the valve structure and provided with means imparting to it a normal tendency to hold all of the valves in a closed position, said rockable spider being movable in a direction under the impulse of an actively working valve to hold others of the valves in the closed position.

9. An engine starter for a six cylinder explosion engine comprising a valve structure with as many differential valves as there are cylinders and also provided with a distributing chamber common to all the valves, each valve controlling communication between the distributing chamber and the respective cylinder, means for supplying fluid under pressure to the distributing chamber, and an interconnecting means between the valves comprising rockable spiders each controlling a group of alternate valves corresponding in number to the relation of the number of spiders to the number of cylinders of the engine.

10. An engine starter for a six cylinder explosion engine comprising a valve structure with as many differential valves as there are cylinders, and also provided with a distributing chamber common to all the valves, each valve controlling communication between the distributing chamber and the respective cylinder, means for supplying fluid under pressure to the distributing chamber, and an interconnecting means between the valves comprising two triangular spiders in superposed relation and each rockable with reference to the other on a common support, each spider controlling three alternate valves, and means tending normally to move the spiders in a direction to close all the valves.

11. An engine starter for multi-cylinder engines provided with means for supplying fluid under pressure, and interconnected differential valves controlling the flow of such fluid to respective engine cylinders, the valves being related to the engine cylinders to become selective to the cylinder having

its piston in position for an active forward stroke.

12. An engine starter for multi-cylinder explosion engines, comprising a selector for automatically directing fluid under pressure to the engine cylinders and provided with a plurality of interconnected differential means each adapted to control the flow of fluid under pressure to a respective engine cylinder and each constructed to respond to

the fluid under pressure to control the other differential means through the interconnections therewith.

In testimony whereof I have affixed my signature in presence of two witnesses.
